TUMBLER

George Sakier, New York, N. Y., assignor to Fostoria Glass Company, Moundsville, W. Va., a corporation of West Virginia

Application January 5, 1951, Serial No. 13,675

Term of patent 14 years

(Cl. D36—8)

To all whom it may concern:

Be it known that I, George Sakier, a citizen of the United States of America, residing at New York city, in the county of New York and State of New York, have invented a new, original, and ornamental Design for a Tumbler, of which the following is a specification, reference being had to the accompanying drawing, forming a part thereof, wherein:

Fig. 1 is a side elevational view of a tumbler showing my new design;

Fig. 2, a top plan view;

Fig. 3, a bottom plan view; and

Fig. 4, a section on the line 4—4 of Fig. 2.

The dominant feature of the instant tumbler resides in the convex base ornamented by four sets of festoon-like protuberances, the successive sets being disposed in inverse relation to each other as shown.

I claim:

The ornamental design for a tumbler, as shown and described.

GEORGE SAKIER.
